[57] CLAIM

The ornamental design for a paging radio receiver, as shown as described.

DESCRIPTION

FIG. 1 is a front view of our new design for a paging radio receiver;

FIG. 2 is a rear view of our new design;

FIG. 3 is a top view of our new design;

FIG. 4 is a right side view of our new design; and

FIG. 5 is a bottom view of our new design.

The left side side view of our new design is substantially similar to the right side view of our new design.

FIG. 1

FIG. 2

FIG. 3

FIG. 4
